SLIDING BASE CAN OPENER

Raymond A. Withers, Belmont, Calif.

Application April 16, 1956, Serial No. 578,355

7 Claims. (Cl. 30—10)

This invention relates to improvements in can-opening devices and has particular reference to those can-opening devices of the character in which the end of a can is punctured to provide a pouring opening for liquid contents.

The principal object of this invention is to provide an improvement in can-opening devices of the character having a pinch-pin-positioned cutter head and/or can support as illustrated and claimed in my issue Patent No. 2,722,737, dated May 8, 1955, and entitled "Sliding Can Opener."

A further object of this invention is to provide an improvement by which movement of the cutter head or can support, such as would tend to release the cutter head or can support is prevented when a puncturing force is applied to a can in the can-opening operation.

In my prior patent, there is shown a can-punching device in which a can-perforating cutter and/or a can-supporting member are slidably mounted upon a vertically mounted wall bracket and secured by an off-set pinch pin arrangement that will prevent a sliding movement thereof during a can perforating operation. It has been found that in some instances and with certain types of cans, the pressures exerted upon a can during the perforating operation, are such that the blade-supporting member or the can-supporting member may be displaced from their normal operating position and thus render the pinch pin securing means ineffective.

It is, therefore, a further object of this invention to provide means in the form of a slidable can-engaging member that will function to prevent a pinch pin releasing movement of the can-punching element or can support when pressure is applied thereto in puncturing a can.

Other objects and advantages of my invention will be in part evident to those skilled in the art and in part pointed out in connection with the accompanying drawings, wherein there is shown by way of illustration and not of limitation, a preferred embodiment of the invention.

In the accompanying drawings forming a part of this specification and in which like numbers are employed to designate like parts throughout the same,

Fig. 1 is a fragmentary side elevation with portions broken away showing the invention as applied to the cutter carrying member of a can opener;

Fig. 2 is a front view of the device as shown in Fig. 1;

Fig. 3 is an enlarged fragmentary view showing details of construction;

Fig. 4 is a side view of the invention as applied to an adjustable can-supporting member for a can-punching device of the character contemplated;

Fig. 5 is a front view of the device as shown in Fig. 4;

Fig. 6 is an enlarged fragmentary view showing details of the device illustrated in Fig. 4 of the drawing.

For a better understanding of my invention, reference is now made to the accompanying drawing wherein I

2

have shown my invention as applied to a can-punching device of the type illustrated in my aforesaid prior patent and in which a can-cutting or punching element 10 and/or a can-supporting element 11 are mounted for movement along a common supporting rod 12 and respectively held in operative positions thereupon by oppositely disposed pinch pins 13 and 14 which grip the supporting rod and operate to hold the can-punching element 10 and/or the can-supporting element 11 in a fixed position upon said supporting rod 12 when a can is positioned hereupon for a puncturing operation.

The supporting rod 12 is here shown as of channel cross-section and flattened and offset at its extreme ends as a means for mounting upon a wall or other surface by means of screws 15. The can-punching element 10 as here shown carries a can-punching blade 16 which has an operating handle 17 and is pivotally mounted upon an axis 18 below the pinch pins 13.

With this arrangement, it will be seen that as the blade 16 enters into the end of a can, the final movement of the cutting blade 16 will exert a lateral force upon the can which may tend to rock the can-punching element 10 about a fulcrum established upon the supporting rod 12 by the right hand pinch pin 13. Should any such rocking of the element 10 occur, it will be seen that the pinch pins 13 will be rendered ineffective as a means for holding the can-punching blade 16 in an operative position with respect to a can to be punctured.

As a means for rendering the pinch pins 13 effective in holding the can-punching element 10 against movement along the supporting rod 12 when not in use, I provide a plunger 19 which is held in frictional engagement with the supporting rod 12 at a point below the pinch pins 13 by a spring 20.

The blade-supporting element 10 is also provided with thumb pads 21 by which the action of the plunger 19 and the spring 20 may be overcome when it is desired to adjust the position of the can-punching element 10 upon the supporting rod 12.

With this arrangement, it will be seen that by applying pressure to the thumb pads 21, the operator may cant the cutter blade element 10 in a clockwise direction as viewed in Fig. 1 of the drawing and thus release the bight of the pinch pins 13 upon the supporting rod 12. The blade carrying member 10 can then be moved upwardly or downwardly into cooperating relation with the top of a can positioned upon the can-supporting element 11. When the cutter blade 16 is thus brought into puncturing relation against the top of a can, with its operating lever 17 in a raised position, it will be seen that as the cutter blade 16 enters into the can, the forces exerted upon the can will change from a downward direction to a lateral direction. Under some circumstances, it has been found that this lateral force sometimes results in a canting of the blade-supporting element 10 in the manner above described and thus an inadvertent release in the bight of the pinch pins 13 upon the supporting rods 12 and the result is an imperfect puncturing of the can.

To avoid the above possibility, I have by my present invention, as is more clearly shown in Fig. 3 of the drawing, provided a means that will avoid this difficulty. This feature, comprises a slidable abutment 22 which is here shown as mounted upon the blade-carrying element 10 and above the spring-pressed plunger 19 in such a manner that it will be engaged by the side of a can positioned under the can-punching blade 16. The dimension and movement of the slidable abutment 22 is such that the slightest lateral movement of the can being punctured will cause the inner end of the slidable abutment 22 to engage the supporting rod 12 and thus prevent the application of any canting force upon the

blade-supporting element 10 which might result in a release thereof from the supporting rod 12.

In like manner, with the can-supporting element 11 mounted upon the supporting rod 12 as shown in Figs. 4, 5 and 6 of the drawings, I provide a spring-pressed plunger 23, that is located above the pinch pins 14 so that the bight of these pinch pins 14 upon the supporting rod 12 is maintained and effective to prevent a downward movement of a shelf-like can-supporting element 11 prior to the placing of a can thereupon. At this point, it will be seen that when a can-punching force is exerted upon the supporting element 11 through a can there will also be a tendency for the bottom of the can to move laterally when being punched. Therefore, to avoid any canting of the can-supporting element 11 which would release the bight of the pinch pins 14 upon the supporting rod 12, I provide a slideable abutment 24 at this point which will engage the side of the can and be moved inwardly into contact with the supporting rod 12 in the manner similar to that described for the slideable abutment 22. This will prevent any inadvertent canting of the can-supporting element 11 that would release the bight of the pinch pins 14 and thus permit the can-supporting element 11 to drop into an ineffective position. The particular can-supporting element 11 is here shown as having two spaced bracket-like extensions 25 upon which the bottom of the can is adapted to rest when undergoing a punching operation.

While I have, for the sake of clearness and in order to disclose my invention so that the same can be readily understood, described and illustrated a specific form and arrangement, I desire to have it understood that this invention is not limited to the specific form disclosed, but may be embodied in other ways that will suggest themselves to persons skilled in the art. It is to be understood that the form of my invention herewith and described is to be taken as a preferred example of the same, and that various changes relative to the material, size, shape and arrangement of parts may be resorted to without departing from the spirit of the invention or the scope of the subjoined claims. It is believed that this invention is new and all such changes as come within the scope of the appended claims are to be considered as part of this invention.

Having thus described my invention, I claim:

1. In a can-punching device of the character described, the combination of a vertically extending rod-like support, a can-supporting member at the lower end of said support, a slideable mounting for a can-punching blade having offset laterally extending pinch pins by which said slideable mounting is held in any desired position upon said rod-like support above said can-supporting member, a can-punching blade having an operating handle pivotally secured upon said slideable mounting, and means carried by said slideable mounting adapted and arranged when engaged by a can to prevent a pinch pin releasing movement thereof with respect to said rod-like support during a can-punching operation.

2. In a can-punching device of the character described, the combination of a vertically extending rod-like support, means for supporting a can adjacent said rod-like support, a slideable can-punching blade-carrying member having offset laterally extending pinch pins by which it may be held in any desired position above said can-supporting means, a can-punching blade having an operating handle pivotally secured upon said blade-carrying member, and means slidably mounted upon said blade-carrying member adapted and arranged to be engaged by a can when undergoing a can-punching operation and prevent a pinch pin releasing movement of said blade-carrying member as pressure is applied to the can during a punching operation thereupon.

3. In a can-punching device of the character described,

the combination of a support, a blade-carrying member slidably mounted upon said support, said blade-carrying member having opposed pinch pins adapted and arranged to retain said blade-carrying member in a fixed position upon said support, a can-punching blade having an operating handle pivotally mounted upon said blade-carrying member and normally operating in conjunction with such pinch pins to hold said blade-carrying member in an operative position upon said support when a can is being punched, spring means upon said blade-carrying member also operative to maintain said pinch pins in operating engagement with said supporting rod, and means carried by said blade-carrying member operative to prevent a release of said blade-carrying member by lateral force as said can-punching blade completes a can-punching operation.

4. In a can-punching device of the character described, the combination of a support, a blade-carrying member slidably mounted upon said support, said blade-carrying member having opposed pinch pins adapted and arranged to retain said blade-carrying member in a fixed position upon said support, a can-punching blade having an operating handle pivotally mounted upon said blade-carrying member and normally operating in conjunction with such pinch pins to hold said blade-carrying member in an operative position upon said support when a can is being punched, spring means upon said blade-carrying member also operative to maintain said pinch pins in operating engagement with said supporting rod, and a slideable abutment carried by said blade-carrying member and disposed between said support and the wall of a can while being punched operative to prevent a release of said blade-carrying member as said can-punching blade completes a can-punching operation.

5. In a can-punching device of the character described, the combination of a support, a blade-carrying member slidably mounted upon said support, said blade-carrying member having opposed pinch pins adapted and arranged to retain said blade-carrying member in a fixed position upon said support, a can-punching blade having an operating handle pivotally mounted upon said blade-carrying member, spring means carried by said blade-carrying member operative to maintain said pinch pins in operating engagement with said supporting rod, and a slideable abutment carried by said blade-carrying member movable into engagement with said support upon lateral movement of a can while being punched to prevent a release of said blade-carrying member as said can-punching blade completes the can-punching operation.

6. In a can-punching device of the character described, the combination of a vertically extending rod-like support, a can-supporting member at the lower end of said support, having offset laterally extending pinch pins by which said member is held in any desired position upon said rod-like support, and means carried by said can-supporting member adapted and arranged when engaged by a can to prevent a pinch pin releasing movement thereof with respect to said rod-like support during a can-punching operation.

7. In a can-punching device of the character described, the combination of a rod-like support, a can-supporting shelf slidably mounted upon said support having opposed pinch pins adapted and arranged to retain said can-supporting shelf in a fixed position upon said rod-like support, spring means carried by said can-supporting shelf for maintaining said pinch pins in operating engagement with said rod-like support, and a slideable abutment carried by said can-supporting shelf movable into engagement with said rod-like support upon lateral movement of a can-supporting shelf and operative to prevent vertical movement of said shelf during a can-punching operation.
